UNITED STATES PATENT OFFICE.

JACOB BERGSTRESSER, OF BERRYSBURG, PENNSYLVANIA.

MONUMENTAL DAGUERREOTYPE-CASES.

Specification of Letters Patent No. 22,850, dated February 8, 1859.

To all whom it may concern:

Be it known that I, JACOB BERGSTRESSER, of Berrysburg, in the county of Dauphin and State of Pennsylvania, have invented a new and useful Improvement in Glass Monumental Daguerreotype-Cases; and I do hereby declare that the following is a full, clear, and exact description of the same, reference being had to the accompanying drawings, 10 forming a part of this specification, in which—

Figure 1, is a front view of a glass monumental daguerreotype case, exhibiting my invention. Fig. 2, is a transverse section of 15 the same.

Similar letters of reference in each of the figures indicate corresponding parts.

The nature of my invention consists in the combination of the central frame incased by 20 a central raised bead on the rear side of a glass plate with the outer frame incased by an outer raised bead. The central frame and outer frame being cast together on the same glass plate and the outer one being 25 deeper than the inner or central frame.

By this invention, a frame is provided at the center of the glass plate for the reception 30 of a miniature or daguerreotype and a frame for the reception of lettering, foliage or any other devices outside of the picture frame. The picture and devices are kept perfectly air tight as the inner frame receives cement which prevents the insinuation of air, and the outer frame also receives plaster or other 35 substance which completely incloses and surrounds the inner frame and also excludes air from the outer frame.

The raised beads on the back of the glass 40 plate present at a distance, the appearance of raised ornaments formed on the front of the plate and thus the miniature and devices are separated and each is thrown in the back ground, and the front of the glass plate has a pleasing relief given to it. The necessity 45 of having ornaments which would interfere with the molding of the case, in order to relieve the appearance of the same.

It is very essential to use glass frames as

they are cheaper than iron, they are also more durable than iron ones, and retain their 50 neat appearance longer; as glass, unlike iron, is not liable to corrode by contact of moisture therewith.

In the drawings I have represented a daguerreotype case of one ornamental configuration, but it must be evident that various styles and shapes may be adopted.

A, represents the monumental daguerreotype or miniature case, it is made of glass with a rim *a*, projecting from its rear side 60 as shown in Fig. 2, so that it shall have strength and may be easily embedded and firmly set in the cement or other material which is used for confining it in place, on the monument. It also has a bead *b*, projecting 65 in relief from the central portion of its rear side as shown in Fig. 2. This bead incloses the space which receives the daguerreotype or miniature, and is deep enough to receive and contain the same, and also a deep bed of 70 cement *C*, for confining it in place and excluding air or moisture from it. By thus forming a bead on the rear side of the case the miniature appears at a distance as though it were surrounded by an ornament 75 formed on the front of the face of the case, and thus the miniature has the appearance of being thrown in the back ground and the case has an ornamental relieved appearance notwithstanding its surface is plain.

What I claim as my invention and desire to secure by Letters Patent, is—

The combination of the central frame incased by a central raised bead *b* on the rear side of a glass plate with the outer frame 85 incased by an outer raised bead *a*, the central frame and outer frame being cast together on the same glass plate and the outer one being deeper than the inner or central frame substantially as and for the 90 purposes set forth.

JACOB BERGSTRESSER.
